J. K. ROBINSON

VENTILATOR

Filed Aug. 23, 1922

The technical drawing illustrates a device assembly with four views labeled 1, 2, 3, and 4.

- View 1:** A side cross-sectional view showing a vertical assembly. At the top is a curved component (26) with a slot (27). Below it is a horizontal plate (39) with a slot (39). A vertical support (42) is positioned between them. A central vertical rod (23) passes through the support and the plate. A horizontal rod (10) is attached to the support. A circular base (32) is at the bottom, with a vertical rod (44) extending downwards from it.
- View 2:** A top-down view of the circular base (32) and the vertical rod (44) from View 1. The base (32) has a flange (33) and a central vertical rod (44) extending downwards.
- View 3:** A side cross-sectional view showing a vertical assembly. At the top is a curved component (26) with a slot (27). Below it is a horizontal plate (39) with a slot (39). A vertical support (42) is positioned between them. A central vertical rod (23) passes through the support and the plate. A horizontal rod (10) is attached to the support. A circular base (32) is at the bottom, with a vertical rod (44) extending downwards from it.
- View 4:** A detailed view of the top assembly. It shows a vertical rod (23) with a slot (28) at the top. A horizontal plate (39) is attached to the rod (23). A vertical support (24) is positioned between the rod (23) and the plate (39). A circular base (32) is at the bottom, with a vertical rod (43) extending downwards from it.

UNITED STATES PATENT OFFICE.

JAMES K. ROBINSON, OF LITTLE ROCK, ARKANSAS.

VENTILATOR.

Application filed August 23, 1922. Serial No. 583,826.

To all whom it may concern:

- Be it known that I, JAMES K. ROBINSON, a citizen of the United States, residing at Little Rock, in the county of Pulaski and 5 State of Arkansas, have invented certain new and useful Improvements in Ventilators, of which the following is a specification, reference being had to the accompanying drawings.
- 10 This invention relates to improvements in ventilators, and more particularly to a ventilator of the induction type whereby the draft is forced into the building, room or the like to supply fresh air thereto.
- 15 An important object of the invention is to provide in a ventilator of this type embodying a rotatable cowl having means for directing the induction opening thereof into the wind, means whereby the passage 20 of rain water and the like to the interior of the cowl and accordingly to the draft pipe is prevented.

A further object of the invention is to provide a ventilator of this type having a 25 damper which may be closed to prevent the ingress of wind driven rain, snow or the like and which has means for controlling the damper disposed interiorly of the cowl and draft member in such a manner that 30 it does not interfere with the operation of the ventilator.

A still further object of the invention is to provide a device of this character which is simple in its construction and arrangement, durable in service and a general improvement in the art.

These and other objects I attain by the construction and arrangement shown in the accompanying drawings wherein for the 40 purpose of illustration is shown a preferred embodiment of my invention and wherein like reference characters designate like parts throughout.

In the drawings:-

45 Figure 1 is a vertical sectional view taken through a ventilator constructed in accordance with my invention;

Figure 2 is a front elevation thereof;

50 Figure 3 is a section on the line 3-3 of Figure 1; and

Figure 4 is an enlarged detail sectional view showing the manner of mounting the bearing rotatably supporting the cowl.

55 Referring now more particularly to the drawing, the numeral 10 indicates a draft member adapted for connection with a suit-

able pipe (not shown) leading to the room or building to be supplied with air. Adjacent its lower end the draft member 10 is provided with a cross bar 11 upon the upper surface of which is securely mounted a yoke 12, the yoke and cross bar having aligned openings 13 and 14 respectively, which are axial to the draft member 10. Adjacent its upper end the draft member 15 has mounted therein a second cross bar 16 which is provided with an axial opening 17.

The numeral 18 designates a bearing plate seated upon the cross bar 11 and having an opening 19 formed therein aligning with the opening 14 of the cross bar. The upper surface of the bearing plate has a concaved portion 19 surrounding the opening 18 thereof, for a purpose presently to appear. This bearing is held in position upon the cross bar by means of a yoke strap 20 having an opening 21 in its upper surface exposing the concaved portion 19 of the bearing 17 and in its lower surface an opening 22 aligning with the opening 14 of the yoke. A tubular bearing rod 23 is directed through the openings 16 of the cross bar 15 and 13 of the yoke 12 and has applied to its lower end an annular bearing plate 24 curved upon its lower surface with a curvature greater than the curvature of the concavity 19 and adapted to abut thereagainst, in the present instance the lower end of the bearing rod 23 being shown as 25 screw-threaded for coaction with screw-threads formed upon the interior of the annular bearing plate 24.

The numeral 25 indicates a cowl provided with a fin 26 adapted to direct the cowl with its upper end opening to windward. The cowl has seated in the angle bend thereof a plate 27 having a threaded opening formed therein axially aligned with the vertical portion of the cowl and which is adapted for the reception of the threaded upper end of the tubular bearing rod 23. Secured to the cowl adjacent the plate 27 is a downwardly extending member or strap 28 having a horizontal portion 29, the end of which is secured to the cowl and which horizontal portion is provided with an opening 30 through which the bearing rod 23 is directed. Adjacent its lower end the cowl is provided with a cross bar 31 which is likewise provided with an opening 32 through which the bearing rod may be di-

rected and rotated to engage its threaded upper end in the plate 27. The connection between the cowl and member 10 is in the form of a rain tight joint 32 permitting 5 relative rotation of the cowl and member, in the present instance disclosed as a skirt 33 formed upon the lower or eduction end of the cowl and extending into the upper end of the member 10, and a frustoconical 10 flange 34 formed upon the outer surface of the cowl and extending outwardly over the upper edge of the member 10.

The horizontally directed portion of the cowl is formed in two pieces, 35 and 36, the 15 member 35 forming a continuation of the cowl proper and the member 36 being secured thereto and of slightly greater size than the member 35, this excess size being arranged at the lower side of the member 20 35 and projecting beneath the forward edge thereof. The member 35 forms an induction end proper and the member 36 a false induction end. The purpose of the spacing of the lower portions of the members 35 and 36 25 will be obvious when it is pointed out that wind driven rain collecting in the induction end of induction ventilators is blown by the wind passing into the ventilator to a point where it falls within the draft member 10 30 and into the room being ventilated. In the construction at present shown, the lower edge of the induction end being spaced above the lower end of the false induction end, a considerable collection of rain will be necessary 35 before the same could pass into the cowl proper. In order to prevent such a collection, I provide the inner edge of the false induction end with a plurality of openings 37 through which the water may drain off, 40 and furthermore space the inner edge of the false induction end from the cowl proper, as at 38, for the same purpose.

39 designates a butterfly damper disposed in the outer end of the false induction end 45 of the cowl and having its pivot extending through the side walls thereof and provided with springs 40, one end of each of which is secured to the pivot and the other end of which is secured to the section 36. These 50 springs act at all times to hold the damper in the position shown in full lines in Figure 1, so that normally air may pass into this induction end and so to the room to be ventilated. The vertical member 28 has rotatably 55 mounted therein a pulley 41, the edge of which extends immediately adjacent the bearing rod 23, the bearing rod 23 being provided with a slot 42 at this point. A

cable or chain 43 has its ends secured to the butterfly damper 39 and passes over the pulley 43 through the opening 42 and downwardly through the bore of the bearing rod 23. The lower end of this cable passes through the bearing 19 and cross bar 11 and is provided with a ring 44 by means of 60 which it may be hooked to hold the damper in closed position and prevent the entrance of air or flying particles carried by the air during severe storms. Immediately upon release of the cable 43 the damper assumes an 65 open position by reason of the springs 40 and again permits passage of air through the ventilator.

From the foregoing it is believed to be obvious that a ventilator constructed in accordance with my invention will prevent the entrance of wind driven rain and at the same time provides a simple and durable structure which will not readily get out of order and which may be very cheaply produced. It will furthermore be obvious that the construction as hereinbefore set forth is capable of some change and modification without materially departing from the spirit of my 70 invention and I accordingly do not limit myself to such specific structure except as 75 hereinafter claimed.

I claim:—

I. In an induction rotatable cowl ventilator, an induction end comprising a main induction end and a false induction end applied to the main induction end and of greater size than said main induction end, the excess size of the false induction end being disposed at the lower side of the main induction end whereby to form a pocket restraining the passage of liquor into the cowl, and drain openings formed in said 90 false induction end at such pocket.

2. In an induction rotatable cowl ventilator, an induction end comprising a main induction end and a false induction end applied to the main induction end and of greater size than said main induction end, the excess size of the false induction end being disposed at the lower side of the main induction end whereby to form a pocket restraining the passage of liquids into the cowl, a damper mounted within said false induction end, and a rotatable mounting for the cowl including a tubular member forming a housing for an 95 operating element for said damper.

In testimony whereof I hereunto affix my signature.

JAMES K. ROBINSON.
